UNITED STATES PATENT OFFICE.

GUSTAV EMIL HÄNISCH, OF BEUTHEN, GERMANY.

BOILING AND PRECIPITATING TOWER.

SPECIFICATION forming part of Letters Patent No. 477,755, dated June 28, 1892.

Application filed March 8, 1890. Serial No. 342,400. (No model.)

To all whom it may concern:

Be it known that I, GUSTAV EMIL HÄNISCH, a subject of the King of Saxony and German Emperor, residing in the city of Beuthen, German Empire, have invented certain new and useful Improved Boiling and Precipitating Towers; and I do hereby declare that the following is a full, clear, and exact description of the invention, which will enable others skilled in the art to which it appertains to make and use the same.

This invention relates to boiling and precipitating towers or columns for carrying out various chemical processes in which precipitates are obtained from any kind of solution by the introduction of steam or gas, &c.

It has for its object to provide a boiling and precipitating tower which may be worked regularly and continuously for a certain time and which can be completely discharged and cleaned out without loss of time or of the substance treated in the tower.

The invention consists in a construction of the boiling and precipitating tower in two chambers or divisions, so that the one chamber for the boiling-out or precipitating process, closing air-tight and provided with fittings suitable for the purpose, is separated from the other chamber, serving as a passage of access and also closing air-tight by a partition formed by closely-shutting plates or doors located one above another.

In the accompanying drawings, Figure 1 is a vertical section of a boiling and precipitating tower embodying this invention; Fig. 2, a vertical section through line A B of Fig. 1; Fig. 3, a vertical section of a portion of the tower to an enlarged scale; Fig. 4, a horizontal section through line C D of Fig. 3; Fig. 5, a vertical section through a portion of the tower with wood blocks arranged therein.

The tower consists, substantially, of a boarded shaft of considerable height and rectangular in cross-section. The inside of the tower is lined with sheet-lead 1 and made air-tight. The tower or boarded shaft is constructed in two divisions or chambers.

E is the chamber in which solutions or lyes are boiled or precipitates obtained therefrom, to which end it is fitted with inclined planes 2, Fig. 2, or has wood bars 3, Fig. 5, arranged in it. The other chamber F is without fittings

and serves simply as a passage for the workman engaged in clearing out the boiling and precipitating chamber E. The two chambers 55 are separated by a partition made up of single wood plates or planks 4, standing one above another, lined or covered with lead on the inner or chamber E side, and closing air-tight, these plates 4 being held pressed against 60 the shaft-frame by props 5, the edge bearing-surfaces, as well as the butt-joint surfaces of the plates 4, being covered with india-rubber, so as to render a hermetical closure practicable.

If the tower is intended for the treatment of alkaline instead of acid solutions—as, for instance, for the boiling or evaporation of weak ammonia-water with addition of milk of lime—it may be constructed of plate-iron 70 instead of wood with a lead covering.

In order that it may not be necessary to remove the whole of the partition from top to bottom when, as may frequently happen, a stoppage or blocking up of the tower takes 75 place at any part of its height, square iron bars 6, covered with lead, are interposed at certain distances apart—say from two to three yards—to act as bearers each for from four to six plates or planks 4. In order, also, to 80 prevent the necessity of removing the wood bars 3 for the purpose of clearing out the tower, these must not be placed to cross each other, but must all lie in the same direction, with their ends toward chamber F, to allow of 85 the precipitate being withdrawn by means of a long iron tool.

In order, when the cleaning or clearing out operation is in progress, to prevent the precipitate from falling down and accumulating 90 at the bottom in a way to stop up the apparatus, the wood blocks in such a kind of internal arrangement as shown in Fig. 5 are arranged in sets from two to three yards high, one set above the other, each set being 95 separated by a clear distance of about nine inches. In the clearing-out operation a board the shape of the cross-section of the tower is slid underneath a set and receives the falling material. The solutions or lyes from which precipitates are to be obtained pass into the tower through pipe 7. The steam or precipitating gases enter through pipe 8. The waste gases pass away through pipe 9. The pre-

cipitates, &c., are discharged through pipe 10. The lye, formed with the precipitate to a thin paste flowing out of the tower, with addition of lye from the tower, collects in a settling-5 tank, Fig. 2, placed lower down. The precipitate settles to the bottom sooner or later, according to its specific gravity, while clear liquid flows off continuously through upper overflow-pipe 11. Processes of this kind have 10 hitherto generally been carried out in fixed cylinders or casings, several of which are combined so as to form one apparatus. Although this method of working is said to be continuous, yet each element of the apparatus 15 is in turn thrown out of work, and to charge and empty it it must be disconnected from the other elements, during which time its operation is stopped. Therefore, instead of such apparatus it is more advantageous and convenient 20 to employ high boiling-towers, which allow of a very regular and for a certain time continuous working. In conjunction with small attendance requirements, regularity of working, and profitable consumption 25 of steam or gases ascending from below, there are two very important properties possessed by boiling-towers as compared with cylinders and which for certain processes are of great importance and economic value.

30 Taking, for example, the boiling out of a solution of phosphate of lime in sulphurous acid—such as is obtained in the process of extraction from bones by means of sulphurous acid—it has been observed that in the boiling process expulsion of the sulphurous acid as pure gas and precipitation of the phosphoric acid as terphosphate of calcium, there has been in practice the great drawback in the use of evaporating-vessels that the most 35 important evolution of sulphurous acid taking place between 60° and 90° Celsius of temperature causes such a violent soap-like frothing that the larger portion of the charge has to be thrown over to the next vessel of the 40 combined apparatus. The frothing then takes place to a greater extent in the second vessel, greater still in the third, and so on, as each successive vessel has an increased charge. Therefore in practice, in order to avoid frothing 45 over either, very high vessels are used, or these must be worked with a charge of one-third or one-quarter their capacity. This course, however, presents the great disadvantage that the air entering the vessel every 50 time it is charged, say, to the extent of three-fourths of its capacity weakens the evolved gas and renders it unsuitable for reabsorption. Further than this, the precipitation of the phosphate of lime has the disadvantage 55 that a large portion of the sulphurous acid is also precipitated therewith. Notwithstanding an evaporation during several hours of a phosphate solution of 16° Baumé strength, the precipitate contains from fifteen to six- 60 teen per cent. of sulphurous anhydride and the residual lye—that is, the liquid remain-

ing behind after the process of precipitation from 0.5 to 0.6 per cent. of sulphurous acid, while the boiling out of a similar solution in the tower during a space of time of almost 70 two minutes yields a precipitate containing only from seven to eight per cent. of sulphurous acid, corresponding to the quantities of the earths and alkalies present, and a residual lye with only 0.25 per cent. of sulphurous 75 acid. Consequently the performance of the precipitating process in the tower is, in addition to continuous working and a much lower expenditure of steam, of advantage from a double point of view, as, first, the expelled 80 gas—sulphurous anhydride—after condensation of the steam is obtained only in a pure state, and, secondly, the precipitate is almost perfectly free from sulphurous acid.

There are several chemical processes quite 85 analogous to the example cited. In most cases the employment of towers would be preferred for the boiling or treatment of lyes or solutions with gases were it not for an important drawback which has hitherto been the cause 90 of such towers being advantageous to a small extent only. This drawback consists in their liability to a more or less frequent stopping up of their fittings or passages by the formation of sludge, which renders it necessary to 95 put them out of operation for their thorough discharge and clearing out. Attempts have been made to get over the difficulty of the clearing of the internal fittings or to render this easier by arranging at the sides of the 100 tower large cleaning-apertures closable with plates and screws; but in this case the clearing out can only be imperfectly accomplished, especially when the sludge cakes to hardness, as it does in many boiling processes. There 105 is also the evil that the large number of cleaning-apertures required are very difficult to keep tight, and consequently lead to a loss of gas.

In order to allow of boiling and precipitating towers of the kind referred to being easily and thoroughly cleared out without much loss of time and without removal of the internal fittings, I construct and operate them as hereinbefore described.

The difficulty of properly closing the cleaning-apertures has led me to the construction of my double chamber boiling and precipitating tower, the essential feature of which is the removable partition composed of plates 115 located one above another.

What I claim as my invention, and desire to secure by Letters Patent, is—

1. A boiling and precipitating tower consisting of a shaft E, provided with fittings, one 125 side of which shaft communicates with an airtight chamber or shaft and is composed of removable tightly-closing plates located one above another, substantially as described and shown.

2. In a boiling and precipitating tower having a shaft E, provided with fittings, a side or

wall composed of removable tightly-closing plates located one above another, in combination with a fixed bearer to each set of from four to six plates, substantially as described and shown.

5 3. In a boiling and precipitating tower, a shaft E, with a side or wall composed of separate removable tightly-closing plates located one above another, in combination with parallel wood bars located with their ends point-

ing toward said side or wall of shaft E, substantially as described and shown.

In testimony whereof I have signed this specification in the presence of two subscribing witnesses.

GUSTAV EMIL HÄNISCH.
